UNITED STATES PATENT OFFICE

ROY P. M. DAVIS, OF MOUNT UNION, PENNSYLVANIA

BRICKMAKING MACHINE

Application filed January 6, 1928. Serial No. 244,946.

My invention relates to brick making machines and more particularly to means forslicking the brick before removing the latter from the mold.

Heretofore considerable difficulty has been experienced in the use of rotary and other known slickers and so called scrapers due to the fact that in removing the surplus material from the top of the mold, it frequently happened that material from below the surface of the mold would be lifted and removed. Also it frequently happened that the material would not be slicked down to the top of the mold due to insufficient material being removed.

The object of my invention is to overcome the foregoing mentioned disadvantages incident to the use of slickers and scrapers by providing a device which will only remove that material in the mold which is above the surface of the mold.

A further object of my invention is to provide the slicker with means for removing the surplus material or cap from the top of the mold in advance of the slicking operation.

Other and further advantages of my invention will be apparent as the specification is considered in connection with the accompanying drawings, in which:

Figure 1 is an elevation of a portion of a brick making machine showing my invention applied;

Figure 2 is an end elevation of Figure 1;

Figure 3 is a plan taken along line 3—3 of Figure 1 showing slicker bar at opposite positions by means of chain dotted lines;

Figure 4 is a view showing the slicker bar in two positions one chain dotted with crank arms at right angles to position on Figure 3;

Figure 5 is a detail view showing a cutter bar attached to the forward side of the slicker; and

Figure 6 is a detailed modification of the slicker bar.

Referring more particularly to the draw-

ings wherein like reference numerals designate corresponding parts throughout the several views 1 denotes a portion of the frame of a brick machine, comprising uprights or posts 2, and horizontally disposed cross beams 3, 4 and 5.

Mounted upon the beams or supports 5 are a pair of pallet supporting tracks 6 upon which the pallets 7 are adapted to slide. Sectional molds 8 of old and well known construction are supported upon the pallets for movement to and fro upon the tracks 6. A pair of vertically disposed shafts 9 are mounted for rotation in vertical bearings 10, in turn secured to the cross beams or supports 3 and 4. These shafts 9 have bevel gears 11 fixedly mounted on their upper ends which mesh with bevel gears 12, on horizontally disposed shafts 13, mounted in bearing 15, secured to the posts 2. A drive pulley 16 connected to any suitable source of power (not shown) rotates the shafts 13 and the latter in turn, through the gears 11 and 12 rotate the vertical shafts 9.

Connected to the lower ends of the shafts 9 are a pair of crank arms 17, from the free ends of which depend crank pins 18. These crank arms 17 are connected to and support a slicker support 19, comprising a pair of spaced angle beams 20, secured to spacing blocks 21 as by bolts 22. The crank pins 18 extend loosely through openings 23 in the spacing blocks, nuts 24 screwing on the free ends of the pins 18 serving to prevent the pallet support from dropping off the pins. A slicker bar or plate 25 having beveled edges 26 is screwed to the pallet support 19 by means of countersunk headed bolts 27, which pass upwardly through the slicker bar 25 and flanges 28 of the angle beams 20.

It will be noted that the slicker bar is positioned slightly above the plane of travel of the top of the sectional mold 8 so that relative movement of the mold and slicker bar will cause the latter to slick the excess mate-

rial from the top of the former. The height of the slicker bar above the mold and therefore the amount of pressure applied to the mold or material therein can be adjusted in an obvious manner by means of the washers 29 and the nuts 24.

In the modified form of the invention illustrated in Figure 5, a cutter bar 30 is bolted to the slicker bar support 19 by means of bolts 31. This cutter bar is preferably inclined 10 downwardly so that the cutting edge 32 thereof is slightly below the top face of the slicker bar and preferably slightly above the bottom face of the bottom of the slicker bar. 15 This cutting edge 32 may be modified to reduce or in some instances it may be desirable to remove the bevel edge or even reverse the bevel. The inclination of the cutter can be adjusted by employing one or more wedge 20 shaped washers 33, so that the cutter will cut the brick making material to any desired height above the mold in advance of the slicking operation. The inclination of the cutter 30 is primarily of importance in that by altering the angle the working edge of the cutter can be conveniently elevated or lowered 25 according to the kind of brick making material being used.

In the modification illustrated in Figure 6, 30 the slicker bar 25' is formed with a bevel on its upper forward edge, which has been found desirable where material of certain characteristics is used.

While it is thought that the operation of 35 the slicker will be readily understood from the foregoing description, the following brief explanation is given: After the sectional mold has been filled with brick making material, the pallet 7 with the mold 8 thereon is 40 slid along the tracks 6 by the usual mold actuating mechanism (not shown). As the mold passes beneath the slicker bar (which may be held stationary if deemed desirable) the cap or top of the material in the mold is removed 45 by the cutter 30, or in the event the material does not require advance cutting, and the cutter bar is dispensed with, the excess material is removed by the slicker bar. The movement of the mold continues until it is beneath 50 the slicker bar, the latter being of substantially the same width and length as the mold, although the width of the slicker bar may be varied depending upon the character of the brick making material and the 55 length of time that can be devoted to the slicking operation, as may be affected by the various operations of the brick machine. The movement of the mold may be arrested at 60 this point, or continued to carry the mold from beneath the slicker, or the previous movement of the mold may be reserved for this purpose.

Where it is deemed desirable the mold may 65 be slicked while remaining stationary on the

tracks 6 by causing the slicker bar to swing with a circular motion, towards and across the mold. This movement is effected, as previously explained through the drive pulley 16, shafts 13 and 9 and crank arms and pins 70 17 and 18 respectively. Under certain conditions it is desirable to swing or pass the slicker bar across the mold when the latter is in motion, in which event the drive for the pulley 16 and mold pusher mechanism (not 75 shown) will be actuated in synchronism.

Having thus described my invention, what I claim is:

1. In a brick making machine, a mold and mold support, a slicker comprising a slicker bar of substantially the same length as the mold, and means connected to opposite ends of said bar for causing the bar to move across the top of the mold with a translatory circular movement. 80

2. In a brick making machine, a mold and mold support, a slicker comprising a bar having beveled edges, a cutter carried by the slicker bar and having its forward edge beveled reversely to the bevel of the forward edge 90 of the bar, and means for causing relative movement of said slicker and mold towards each other.

3. In a brick making machine, a mold and mold support, a slicker comprising a bar having beveled edges, a cutter carried by the slicker bar and having its forward edge beveled reversely to the bevel of the forward edge of the bar, and means for moving said slicker bar and cutter in a circular path across the 100 top of the mold.

4. In a brick making machine, a mold and support therefor, a slicker bar and support therefor, the forward edge of said slicker bar being beveled on its under face, and a cutter on said bar projecting at an angle beyond and below the forward edge of the slicker bar. 105

5. In a brick making machine, a mold and support therefor, a slicker bar and support therefor, the forward edge of said slicker bar being beveled on its under face, a cutter on said bar projecting at an angle beyond and below the forward edge of the slicker bar, the forward edge of the cutter being beveled 110 on its upper face. 115

6. In a brick making machine, a mold and support therefor, a slicker bar and support therefor, the forward edge of said slicker bar being beveled on its under face, a cutter on said bar projecting at an angle beyond and below the forward edge of the slicker bar and means for adjusting the angularity of the cutter bar with respect to the slicker bar. 120

7. In a brick making machine, a mold and support therefor, a slicker bar and support therefor, and a cutter on said bar having its forward edge below and in advance of the forward edge of the slicker bar. 125

8. In a brick making machine, a mold and 130

support therefor, a slicker bar and support therefor, and a cutter on said bar having its forward edge below and in advance of the forward edge of the slicker bar and means for elevating and lowering the cutter relatively to the slicker bar.

9. In a brick making machine, a mold and mold support, a slicker comprising a non-rotatable member of substantially the same length as the mold, and means for causing the said member to move relatively to the mold across the top thereof with a translatory circular movement.

In testimony whereof I affix my signature.

ROY P. M. DAVIS.
